UNITED STATES PATENT OFFICE

98,678

DESIGN FOR A TRANSIT

Adolph Langsner, Chicago, Ill., assignor to Eugene
Dietzgen Company, Chicago, Ill., a corporation
of Delaware

Application August 25, 1934, Serial No. 53,056

Term of patent 14 years

To all whom it may concern:

Be it known that I, Adolph Langsner, a citizen
of the United States, residing at Chicago, Cook
County, Illinois, have invented a new, original,
and ornamental Design for a Transit, of which
the following is a specification, reference being
had to the accompanying drawing, forming part
thereof.

Figure 1 is a side view of a transit showing my
new design;

Figure 2 is a top plan view; and

Figures 3 and 4 are side views of the same taken
at right angles to each other.

I claim:

The ornamental design for a transit as shown.

ADOLPH LANGSNER.
